(21) Appl. No.: **29/261,363**

(57) **CLAIM**

(22) Filed: **Jun. 12, 2006**

The ornamental design for smart AC 100 watt inverter, as shown and described.

(51) **LOC (8) Cl.** 13-02

DESCRIPTION

(52) **U.S. Cl.** **D13/110**

FIG. 1 is a front elevational view of a smart AC 100 watt inverter showing my new design;

(58) **Field of Classification Search** D13/110,

FIG. 2 is a back elevational view thereof;

D13/107, 118, 144, 199; 320/104; 363/132,

FIG. 3 is a right side elevational view thereof;

363/141, 146; 439/483, 668

FIG. 4 is a right-front view thereof;

See application file for complete search history.

FIG. 5 is a bottom plan view thereof;

(56) **References Cited**

FIG. 6 is a left elevational view thereof; and,

U.S. PATENT DOCUMENTS

FIG. 7 is a top plan view.
